PORTABLE TOILET

Harry W. Brown, Rte. 1, Box 220, Artesian Ave., Big Bend, Wis., and Kenneth R. Fisher, N52 W15412 Elrio Drive, Menomonee Falls, Wis.

Filed May 6, 1965, Ser. No. 85,229

Term of patent 14 years

(Cl. D4—5)

FIG.1

FIG. 1 is a side elevational view of a portable toilet showing our design.

The side opposite that shown in FIG. 1 is a mirror image thereof.

FIG. 2 is a plan view illustrating the appearance of the device when looking at it from above relative to FIG. 1.

FIG. 3 is an elevational view illustrating the appearance of the device when looking at it from the left relative to FIG. 1.

FIG. 4 is an elevational view illustrating the appearance of the device when looking at it from the right relative to FIG. 1.

We claim:

The ornamental design for a portable toilet, as shown and described.
